SELF-PROPELLED DIVER TOW OR THE LIKE

Wesley K. Markham, 1147 Greenridge Road,
Jacksonville, Fla. 32207

Filed Jan. 15, 1975, Ser. No. 541,081

Term of patent 14 years

Int. Cl. D12—14

U.S. Cl. D12—65

FIG. 1 is a top plan view of the self-propelled diver tow showing my new design;

FIG. 2 is a bottom view thereof;

FIG. 3 is a front end view taken along line 4—4 of FIG. 1;

FIG. 4 is a rear end view taken along line 3—3 of FIG. 1;

FIG. 5 is a left side elevational view taken along line 5—5 of FIG. 3; and

FIG. 6 is a right side elevational view taken along line 6—6 of FIG. 3.

I claim:

The ornamental design for a self-propelled diver tow or the like, substantially as shown.
